UNITED STATES PATENT OFFICE.

PATRICK P. LA MONTAGNE, OF BOURBONNAIS, ILLINOIS, ASSIGNOR, BY MESNE ASSIGNMENTS, TO POPE MACHINE COMPANY, OF KANKAKEE, ILLINOIS, A CORPORATION OF ILLINOIS.

KNITTING MACHINE AND NEEDLE THEREFOR.

Application filed August 28, 1918, Serial No. 251,808. Renewed December 5, 1922.

To all whom it may concern:

Be it known that I, PATRICK P. LA MONTAGNE, a citizen of the United States, residing at Bourbonnais, county of Kankakee, 5 State of Illinois, have invented an Improvement in Knitting Machines and Needles Therefor, of which the following description, in connection with the accompanying drawing, is a specification, like characters 10 on the drawing representing like parts.

This invention relates to a separate latch knitting machine needle, that is, a needle of the type in which the hook member and latch member are separate members physically independent but co-operating to perform the 15 required knitting functions.

It is the object of the invention to provide a separate latch knitting machine needle of this type which may be mounted and 20 operated in the needle slot of the needle bed without the necessity of providing a complete separate slot for the latch member such as is frequently employed in connection with this type of needle, it only being necessary 25 to provide in the preferred form of the needle illustrated a small clearance slot or recess for a portion of the latch at the outer end of the needle bed. This feature of the invention enables the separate latch type of 30 needle readily to be employed in existing knitting machines without rendering any substantial reconstruction thereof necessary.

It is the further object of the invention to provide a separate latch needle so constructed 35 that the co-operating movements of the members may be effected without placing any undue strain upon the work and consequently without unnecessarily expanding the stitches during the retracting movement.

It is the further object of the invention to 40 provide a separate latch knitting machine needle which may be adapted for use in various types of knitting machines and which may readily be substituted for any form of 45 knitting machine needle wherever the same is used.

These and other objects and features of the invention will appear more fully from the accompanying description and drawings 50 and will be particularly pointed out in the claims.

In the drawings, which show a well known and ordinary type of circular knitting ma-

chine with a preferred embodiment of the present invention,

55

Figure 1 is a view chiefly in central vertical cross-section of a portion of the knitting machine;

Fig. 2 is a detail in transverse cross section showing the connection between the needle projecting cam ring and the needle retracting cam ring;

Fig. 3 is a side elevation partially in vertical cross section of a portion of the cylinder of the machine and a needle embodying 65 the preferred form of the invention, the needle being shown in projected position;

Fig. 4 is a similar view of the needle shown in retracted position;

Fig. 5 is a view in elevation looking toward 70 the left of the needle shown in Fig. 3, with a portion of the hook member broken away to show the latch member;

Fig. 6 is a view in transverse cross section of the needle taken on the line 6-6 Fig. 3; 75

Fig. 7 is a view similar to Fig. 6 showing a slightly different construction of the latch member;

Fig. 8 is a development of the preferred form of latch member;

80

Fig. 9 is a side elevation of the jack;

Fig. 10 is an end elevation looking toward the left of Fig. 9 of the jack;

Fig. 11 is a transverse cross section enlarged of the jack taken on the line 11-11 85 of Fig. 9.

The invention is adapted for use as has already been pointed out in any ordinary type of knitting machine and with the usual modification for use in any position in the 90 machine. For the purpose of illustrating the invention the needle is herein disclosed as a type adapted for use as a cylinder needle in the cylinder of a circular knitting machine.

For convenience in disclosing the invention the movement of the needle to yarn receiving position will be referred to as the "projecting movement" or movement to "projected position"; movement of the needle in the opposite direction will be referred 100 to as the "retracting movement" or the movement to "retracted position"; the direction toward the needle bed will be referred to as "inner" and the direction away from the needle bed as "outer"; direction toward the 105 hook end of the hook member or the point

of the latch member as "forward" and the opposite direction as "rearward"; direction lengthwise of the hook and latch members will be referred to as "longitudinal"; direction through the members from face to face as "lateral"; and direction in or parallel with the general plane of the members as "transverse"; but it will be understood that these and similar terms are relative only 10 and are not to be taken as otherwise limiting the invention.

The knitting machine needle comprises the two separate and independent members, the hook member 12 and the latch member 13. In this general type of needle one of the members is actuated from the other which in turn is actuated by cams of the knitting machine, and, in the preferred form shown, the latch member receives its actuation 15 from the hook member. The hook member in the form illustrated is provided with a shoulder 14 to co-operate with the projecting cam of the machine while the shank 15 of the hook member is provided with a shoulder 16 which in this case co-operates 20 with a separate jack which in turn is actuated by the retracting cam of the machine and the operation of which will be set forth later.

30 Forward of the shank 15 or at the forward end of the shank the hook member is enlarged transversely to form the body portion 17 and this body portion is provided with an opening 18 extending laterally therethrough. The end walls 19 and 20 present or constitute shoulders which contacting with the latch member insure the proper relative movement of the needle members.

The hook member is slotted longitudinally 40 and transversely at its forward end at 21 to 22. This slot opens into the lateral opening 18 and at its forward portion 21 extends entirely through the hook member transversely thereof. This slot is preferably 45 formed by a sawing operation and the configuration of the needle is so arranged as to enable the ordinary type of circular saw to be employed; for example, the body portion is cut away so as to enable an ordinary 50 size saw 23 indicated in three different positions on the inner edge of the hook member to cut this slot. A recess 24 is provided on the outer face of the hook member connecting with the slot 21 and this recess may 55 be formed by the saw 23 operating on the outer face, while the guiding shoulder 25 connecting the recess and slot may be formed by a smaller saw 26 moving along the line 27. A small notch or recess 28 is 60 formed on the outer face of the tip of the hook to receive the latch point.

The latch member 13 is made of thin sheet metal and of such thickness that it may readily move in the slot 21-22. At its forward 65 end it presents the head 29 having the out-

wardly and forwardly inclined latch point 30. On its outer face the point meets the head in a smooth curve 31 forming a seat in which the stitch to be cast off may rest during the retracting movement of the needle. 70 The rearward end of the shank of the latch member has a portion 32 shown developed in Fig. 8 extending transversely from the main body of the shank. In the completed latch this portion is bent back upon itself 75 to bring the edge 33 in line with the edge 34 and then a sharp bend or crease is formed in one or both of the sides so as to give the shape shown in cross section in Figs. 6 or 7 respectively. When but one side of the butt 80 of the latch thus formed is bent or creased as on the line 35 the shape is as shown in Fig. 6; when both sides are bent as on the lines 36 the shape is as shown in Fig. 7. In either case the side walls of this butt section of the latch yield with respect to each other without danger of cracking or splitting the metal of which the latch member is formed. The butt section of the latch thus formed is bent so as to present a yielding or resilient cross section somewhat greater than the thickness of the hook member and of sufficient thickness frictionally to engage the side walls of the needle slot and effect the required retarding action with respect to the movement of the hook member. The shank of the latch member, forwardly of the butt is bent laterally at 37 so as to bring it into the medial plane of the hook member. 95

The butt portion of the latch presents at its rearward and forward ends suitable shoulders 38 and 39 for cooperating respectively with the shoulders 19 and 20 of the hook member. The contracting areas of these pairs of shoulders is made relatively small to prevent any accumulation of dirt between the shoulders which would vary the accuracy of operation of the needle members. This result is secured in the case of 105 the contacting shoulders 19 and 38 by cutting away the latch butt at 40 and in the case of the contacting shoulders 20 and 39 by making the shoulder 20 of small area. 110

Both the hook member and latch member are formed of sheet metal of the required thickness preferably by stamping or cutting operations. This enables both members to be formed with extreme accuracy and insures all the members of a given size being 115 exactly alike which is highly important both to accuracy of operation in the completed needle and to low cost of manufacture. By thus stamping or cutting out these members the co-operating shoulders by which the 120 members are operated are accurately positioned with respect to the effective or operating portions.

The needle is assembled by inserting the point of the latch member into the opening 130

18 and through the slot 22—21 until the extreme point rests against the shoulder 25 and projects into the recess 24. Then the latch butt will snap into place in the opening 18. The members will remain thus assembled because when the shoulder 38 is in contact with the shoulder 19 the point of the latch is prevented from passing inwardly by the shoulder 25. The needle when thus assembled presents a self-contained structure in which the latch member is in position in the hook member and is not readily separable therefrom. This complete self-contained needle may therefore be shipped to the user, stored by the user, and inserted by the user as an entity in the slot of the knitting machine in the usual manner.

The needle is shown in connection with a well known type of circular knitting machine in Fig. 1. The machine shown comprises a bed plate 41 in which is vertically and centrally mounted a vertically movable cylinder carrier 42. This cylinder carrier supports the usual needle cylinder 43 in the periphery of which are formed the radial needle slots 44. A skeleton cylinder is shown mounted in the bed plate concentrically with the needle cylinder and provided with the vertical spaced bars 45, but such a device is not necessary and is shown because usually employed in this type of machine.

The needle cylinder 43 is shown as carrying at its upper end an annular sinker cylinder 46 and an annular sinker guide 47 in which the sinkers 48 reciprocate radially. The effective end of the cylinder over which the stitches are drawn is therefore the upper surface 49 of the sinkers when this construction is employed.

The needle may be operated in any suitable manner but when some of the needles are to be thrown out of and into action as in reciprocating knitting it is preferably operated in connection with a separate jack of the general type disclosed in my application No. 205,979 filed December 7, 1917. The use of the separate jack enables the needle to be thrown out of action and returned to knitting position when required with the minimum amount of movement, with the minimum amount of friction, and without danger of binding or breakage. The separate jack renders it unnecessary to project the needle beyond its normal yarn receiving position in order to throw the needle out of action because it is only necessary to project the separate jack independently of the needle to a position where it will not be acted upon by the retracting cam.

In the preferred construction illustrated the separate jack is arranged to operate in the needle slot and rearward of the needle.

This separate jack as shown in Figs. 9, 10 and 11 is also preferably formed out of

sheet metal by a stamping or cutting operation so as to form the shoulders thereof with extreme accuracy. It comprises a shank 50 having at its forward end an outward projection 51, presenting a shoulder 52 to cooperate with the shoulder 16 of the hook member of the needle. Near its rear end it is provided with the outwardly projected butt 53 which projects between the bars 45 of the skeleton cylinder, when used, and which is acted upon by the retracting cams. In the rear of the butt 53 the separate jack may be provided with divergently bent fingers 54 and 55 to pass behind adjacent bars of the skeleton cylinder and thus prevent any danger of the jack coming out from the needle slot. The shank 50 of the jack is bent slightly as shown in Fig. 10 so that when the jack is placed in its slot it will have friction with the walls of the slot.

The usual retracting cam 56 is carried by the cam ring 57 mounted in the bed plate 41 to rotate concentrically with the cylinder in the usual manner and driven by the gear ring 58 from the gear 59 in the usual manner. This retracting cam 56 acts upon the jack butts 53 and has associated with it a projecting cam 60 formed in the cam ring 57 also acting upon the jack butts.

The projecting movement of the needle is however given by a separate projecting cam 61 formed in a projecting cam ring 62 rotarily supported in the sinker guide 47. This cam ring 62 is shown as flanged at 63 and held in place by a flange ring 64 screwed to the bottom surface of the sinker guide 47. Rotation of the projecting cam ring 62 is secured by connecting it to the usual cam ring 57. This connection may be made by a post 65 secured at 66 to the cam ring 57 and projecting upwardly therefrom into an opening 67 formed in a lug 68 projecting laterally from the projecting cam ring 62. Set screws 69 in the lug 68 contact with the post 65 and enable an accurate relative adjustment to be made between the two cam rings.

The projecting cam 61 acts upon the shoulder 14 formed upon the hook member of the needle and gives the projecting movement to the needle.

The retracting movement of the needle is given through the agency of the jack and is effected by the retracting cam 56 acting upon the jack butt 53. The jack projecting cam 60 is for the purpose of insuring the jack butts being left in proper position to cooperate with the cam and picker mechanism such as is usually employed for throwing the needles out of and into action.

In this type of machine the stitch is lengthened and shortened by raising and lowering the cylinder which in Fig. 1 is shown at its highest point. When the cylinder is lowered the shoulders 52 of the jack and 16 of

the needle stand separated because the cam 61 moves with the cylinder. This insures that the needle in projected position shall always occupy the same relative position 5 with respect to the effective top of the cylinder over which the stitches are drawn.

The cam 60 functions particularly, when the co-operating shoulders of the jack and needle are separated, to raise the jacks into 10 proper relation with respect to the usual cam, picker, and dropper mechanism for throwing needles out of and into action, the jack butts when they ride over the portion 70 of this cam being left in proper position. 15 The cam 60 is relieved or cut back throughout its periphery between the points 70 so that when the cylinder is raised or lowered to lengthen or shorten the stitch only a few of the jacks over the portion 70 are moved in 20 their slots. Hence the force required, to raise and lower the cylinder is reduced.

When one or more needles are to be thrown out of action the proper cam or picker mechanism acting upon the jack butt 53 elevates 25 the required number of jacks without in any way changing the position of the corresponding needles to a position where they are caught by and slide along the top of the cam 56. Thus the corresponding needles are 30 prevented from receiving any retracting movement and consequently remain out of action. To restore these needles into action the jack butts 53 are acted upon by the usual cam or dropper mechanism to bring them 35 into the path of the retracting cam 56.

The yarn 71 may be fed in any suitable manner as through a guide eye 72 which extends beneath the hook of the hook member of the needle.

40 The needle is shown much enlarged in Figs. 3 and 4. In Fig. 3 the upper portion of the cylinder 43 is shown and at 73—73 is indicated the effective top of the cylinder which in the present case is formed by the 45 sinkers, this being the edge or surface over which the stitch is drawn during the knitting operation. The line of the inner edge of the hook member of the needle which coincides with the bottom of the needle slot 50 is prolonged forwardly at 74 in order to show the construction of the needle.

It will be understood that the yarn is fed into the hook when the needle is in the projected position shown in Fig. 3 and at this 55 time the previous loop or stitch of yarn surrounds the hook member at the line 73—73. As the needle is retracted this previous loop or stitch must slide forwardly relatively to the needle and finally be cast off over the 60 hook end. During this retracting movement of the needle the latch member moves relatively to the hook member until the latch point closes over the hook with the extreme point resting in the recess 28 in the hook 65 tip. It will be evident that after the latch

has closed over the hook and the stitch is lying at the point 75 indicated in Fig. 4 the movement of the stitch relatively to the needle in casting off, from the point 75 until it is entirely cast off, inherently requires an 70 expansion of the loop or stitch. This expansion cannot be prevented and is inherent 75 to the nature of a latch needle. In this construction the expansion of the loop is made as small as possible because the latch 80 point seats in the recess 28 thus making the maximum across section of the latch member and hook member where casting off takes place the minimum possible. At this time also it will be noted that the latch point is bridged, being supported at both ends and so is capable of taking the necessary strain and at the same time can be made as small as possible.

But it will be remembered that in the knitting operation several needles are simultaneously being acted upon by the retracting cam 56 and are in different states or positions of retraction. If these stitches are expanded to any extent it places a great strain 90 upon the work and may result in rupture or cutting of the yarn. One important feature of this invention is the preventing of the expansion of the stitches other than that essential to the casting off operation.

To secure this result the forward end of the hook member, or that portion forward of the usual cheek, is set outwardly from the line 74 of the inner edge of the hook member as shown in Fig. 3. Preferably the construction is such that the outer face of this offset portion is about parallel to the needle bed or the inner edge of the hook member. This practically eliminates the usual projecting cheek and enables the latch point to 105 lie concealed in the inclined portion of the hook member joining this offset portion to the shank. This inclined portion is preferably of the same cross section as the offset portion and has the same inclination as the latch point. When the needle is in its projected position the inclined point of the latch member lies in the recess 24 and slot 21 against the shoulder 25 in this inclined portion of the hook member with its point covered. Thus the entire cross section of the needle may be reduced to a minimum at the point where the point of the latch rests, 110 eliminating the usual cheek. In the rear of this point the latch may extend as shown 115 slightly inwardly from the line 74 of the inner edge of the hook member. But this slight inward projection of the latch member when the needles are in projected position is of no practical consequence, as it 120 does not strain the stitches while casting off. If there should be any tendency to strain the stitches it is taken care of by relieving the cam 61 as shown at 76 all the 125 way around except immediately adjacent the 130

effective portions whereby the needles are allowed to retract slightly and thus reduce the cross-section. The shank of the latch member in order to strengthen the latch member and prevent its twisting in the longitudinal and transverse slot of the hook member may be and preferably is widened out in the rear of the head as shown and the needle bed will be grooved at 77 at its forward 10 end to receive this portion of the shank of the latch member.

The offsetting of the forward hook end of the hook member prevents the latch point from having to move materially back of 15 the hook member and also enables the yarn to be fed directly beneath and readily to be caught by the hook. The stitches held on the needles therefore stand in a circle of somewhat larger diameter than they would otherwise; hence in such a knitting operation as 20 ribbing the take-up puts a heavier strain on the stitches being cast off without placing too much strain on the remaining needles.

Owing to the fact that the hook end of the 25 needle is offset and recessed on its outer face, and the fact that the inclined point of the latch is, when the needle is in projected position, buried in the inclined portion of the hook member joining the offset hook portion 30 and the shank, it will be seen that the total cross section along which the stitches slide during the retraction of the needle is not increased until the latch has closed over the hook.

35 During the retracting movement of the needle the latch point is cammed outwardly by reason of its inner curved surface contacting with the shoulder 25. The stitch to be cast off hangs about the two members at 40 the point of crossing and so is not expanded as the latch point moves outwardly. As the needle continues its retracting movement with the latch point projected outwardly, the latch point slides along in the recess 45 of the hook member which recess is preferably about equal in cross section to the cross section of the latch point at its base. Consequently the stitch slides along without being expanded until the latch point 50 contacts with and closes over the hook tip. Then upon the further retracting movement of the needle the expansion of the stitch inherent to casting off begins.

Thus it will be seen that there is no substantial change in the total cross section of the needle occupied by the stitch being cast off, from the time the projection of the latch point begins and until it closes upon the hook tip. That is to say, the cross section indicated at 75 is not increased during the projection of the latch point and during the travel of the latch point throughout the length of the recess 24. From this it follows that little friction is required between the latch member and the slot in the

needle bed because there is little or no danger of the yarn during the retracting movement of the needle dragging the latch rearwardly and so preventing closure. Hence it is sufficient that the latch member shall 70 have only a slight frictional engagement with the walls of the slot or substantially that necessary to support the weight of the latch if it be in a vertical position. When a dial is used in connection with the cylinder so as to produce ribbed work the needle cylinder is preferably made somewhat smaller in diameter than usual to compensate for the offsetting of the hook end of the needles and sufficiently to restore the 80 relation between the dial and cylinder needles.

The construction is so arranged that both hook member and latch member have a normal tendency to remain in contact with 85 the bottom or inner wall of the slot in the needle bed. This is effected with respect to the hook member by having the line between the shoulder 16 and the hook of the needle inside of the line where the latch 90 butt frictionally engages the walls of the slot, and with respect to the latch member, by having the point of contact between the shoulders 20 and 39 also inside of the line where the latch butt frictionally engages 95 the walls of the slot. Hence when the retracting pull takes place on the needle the tendency is always to hold the entire needle both latch member and hook member against the needle bed. 100

This application is subsidiary to my application No. 362,878, filed March 2, 1920, which is a continuation of this application and contains the broad claims to the subject matter herein disclosed. 105

Having fully described my invention, what I claim as new and desire to secure by Letters Patent is:

1. A knitting machine comprising a needle cylinder provided with longitudinal 110 needle hook member slots and relatively short longitudinal latch member slots adjacent the forward ends thereof and centrally and radially aligned therewith, separate latch needles, each comprising a hook 115 member and a latch member, the hook members being provided with outwardly offset hooked ends and mounted for reciprocation in said hook member slots, the latch members reciprocable longitudinally and transversely within and with respect to the hook members and having shank portions movable into said latch member slots, whereby the relative movement of the needle member which takes place during the retracting 120 movement of the needle prior to the closing of the latch upon the hook may take place without placing an undue strain on the stitch during its movement from its position on the needle when projected to its 125 130

position on the needle immediately prior to the casting off over the closed hook.

2. A knitting machine comprising a needle cylinder provided with parallel longitudinal peripheral slots to receive needle hook members and with relatively short parallel longitudinal slots adjacent the forward end of the cylinder centrally and radially aligned with the hook member slots to receive and guide the needle latch members.

3. A separate latch needle for knitting machines comprising a hook member and a latch member, the hook member having a

laterally apertured body portion with a straight inner edge, the latch member mounted within the hook member and partially within the lateral aperture for movement longitudinally and transversely thereof and having a portion of its shank projecting inwardly beyond the straight inner edge of the body portion of the hook member when the latch member is closed upon the hook member.

In testimony whereof, I have signed my name to this specification.

PATRICK P. LA MONTAGNE.
